UNITED STATES PATENT OFFICE.

AARON D. JACOBUS, OF NEWARK, NEW JERSEY.

HORSE-BELL.

SPECIFICATION forming part of Letters Patent No. 278,709, dated June 5, 1883.

Application filed September 22, 1882. (No model.)

To all whom it may concern:

Be it known that I, AARON D. JACOBUS, a citizen of the United States, residing in the city of Newark, county of Essex, and State of New Jersey, have invented certain new and useful Improvements in Horse-Bells, fully described and represented in the following specification and the accompanying drawings, forming a part of the same.

10 My invention relates, chiefly, to the bells attached to the collars of horses when harnessed to horse-cars and similar vehicles, and is designed to provide a new and economical means of securing the tongue inside the bell. Such 15 bells require no handle, and are commonly provided with a shank, to which a leather loop is attached for connecting them readily with the harness by a strap. The tongue in such bells has heretofore been held inside the bell by a 20 staple cast inside the crown of the bell, the tongue being commonly cast of hard gray iron with an eye at the upper end, as shown in the 25 annexed drawings in Figure 1. Such staple, being cast into the crown of the bell with the tongue attached to it, would form an inseparable attachment for the latter until the staple wore through. As the tongue is commonly 30 made of cast-iron and the staple of wrought, the latter is nearly always worn through first, when it is almost impossible to secure the tongue in 35 its place, and the entire bell is unfitted for further use.

My improved construction is shown in the annexed drawings, in which Fig. 1 is an edge 40 view of a bell with leather loop attached to its shank. Fig. 2 is a vertical section of the same in a plane at right angles to the first view, on line $x-x$ in Fig. 1. Fig. 3 is a plan of the bell. Fig. 4 is a detached view of a solid link, and 45 Fig. 5 a detached view of a tongue adapted to hook into the same.

A is the bell; B, the tongue; C, the link, and D the shank of the bell, heretofore used chiefly for the attachment of the leather loop E. Into 50 this shank the ends of the staple were formerly cast by inserting the latter in the mold in the usual manner, and the loop was commonly secured to the shank by a transverse pin riveted over at the ends. In my construction the shank is formed with an internal cavity or recess, F, and a removable link, C, is joined to the tongue

and held by one end in the recess F by the transverse pin H. This pin is shown in the drawings as provided with a head and nut, so that it may be readily removed and replaced, 55 as it has the new function in my device of retaining the link in the bell or permitting the removal of the same at pleasure. By this construction the link may be renewed when worn out, or the tongue be detached from the link 60 and a new tongue connected therewith, if necessary.

In Fig. 2 the link is shown as open at one side, so that a solid cast eye formed upon the top of the tongue may be readily hooked thereon; but in Fig. 4 I have shown a solid link, and in Fig. 5 a construction for the eye of the tongue adapted to engage with it.

The eye a in Fig. 5 is shown formed as an open hook, and with this construction would 70 require to be made of malleable cast-iron, so as to be closed upon the link when hooked thereon.

As both tongue and link are readily removable from the bell by the mere withdrawal of the 75 pin H, it is obvious that either can be detached from the other and the worn part renewed without any material cost of time or new parts. A bell may thus be made to last for many years, whereas the constant jingling of the tongue in 80 the bells used on car-horses frequently cuts through the fixed staple in a few weeks and renders the entire bell useless.

To increase the durability of the link C, in my construction I make the part in contact 85 with the tongue of increased thickness, to compensate in some degree for the relative hardness of the metal used in the tongue, the link being preferably made of malleable iron when shaped as in Fig. 2, that the ends may be bent to- 90 ward one another, if necessary. By a proper adjustment of the length of the leather ends below the cross-pin H to the length of the link C, the latter may be drawn tightly up into the recess F when the pin is inserted, and the link 95 kept from rattling and wearing on the pin. For this object the openings in the shank D for the insertion of the pin may be slotted, as shown at b in Fig. 2, so that the level of the pin can be adjusted to the top of the link in 100 the manner suggested.

If preferred, the pin can be inserted in round

holes in the sides of the shank and the link formed with a solid eye at the top, like that shown at the end of the tongue in Fig. 1.

Having thus described my invention, it will be seen that it does not consist in making a removable tongue, as that has previously been done by other means, nor in making the attachment of the tongue to the bell removable, as a wire eye is often constructed to pass through a hole in the top of a bell and be held therein by a nut on the handle or by riveting; but as the class of bells to which my invention relates is not constructed with a handle, and is always used with a transverse pin across its center line for fastening it to a leather loop, as shown, it cannot be provided with any of the means referred to for detaching the tongue or renewing its connection with the bell. My invention therefore consists in utilizing the said cross-pin to hold a removable link inside a hollow shank, and thus making the pin the instrument for removing the tongue, instead of an obstacle, as heretofore.

I therefore claim my invention as follows:

1. The combination, in the horse-bell having 25 the shank D, of the recess F, link C, and transverse pin H, the whole arranged and operating to hold the tongue removably in the bell, substantially as and for the purpose set forth.

2. The combination, in the horse-bell having 30 the shank D, of the link C, fitted into the recess F inside the shank, the loop E, having ends fitted to opposite sides of the shank, and the pin H, fitted transversely into the shank and holding both strap and link in place, substantially as set forth.

In testimony whereof I have hereunto set my hand in the presence of two subscribing witnesses.

AARON D. JACOBUS.
